US0D1029236S

(12) **United States Design Patent** (10) **Patent No.:** **US D1,029,236 S**
(45) **Date of Patent:** **** May 28, 2024**

(54) **FLUID POUCH ASSEMBLY**

(71) Applicant: **Luminoah, Inc.**, Charlottesville, VA (US)

(72) Inventors: **Joseph Neal Piper**, Charlottesville, VA (US); **James Landon Gilkey**, Charlottesville, VA (US); **Brian Bergeron**, Charlottesville, VA (US); **Hill Johnson**, Charlottesville, VA (US); **Martin Eric Weiner**, Charlottesville, VA (US)

(73) Assignee: **Luminoah, Inc.**, Charlottesville, VA (US)

(**) Term: **15 Years**

(21) Appl. No.: **29/849,696**

(22) Filed: **Aug. 12, 2022**

(51) **LOC (14) Cl.** **24-01**

(52) **U.S. Cl.**

USPC **D24/108**; D24/118

(58) **Field of Classification Search**

(57) **CLAIM**

The ornamental design for a fluid pouch assembly, as shown and described.

DESCRIPTION

FIG. 1 is a perspective view showing our new design of a fluid pouch assembly;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown in the drawings are for the purpose of illustrating the bounds of the claim and form no part of the claimed design.

1 Claim, 5 Drawing Sheets
